(57) **CLAIM**

The ornamental design for a tube light for photography and video, as shown and described.

DESCRIPTION

FIG. 1 is a perspective view of a tube light for photography and video showing my new design;

FIG. 2 is a front view thereof;

FIG. 3 is a rear view thereof;

FIG. 4 is a left view thereof;

FIG. 5 is a right view thereof;

FIG. 6 is an enlarged top view thereof;

FIG. 7 is an enlarged bottom view thereof;

FIG. 8 is an enlarged view of the selected portion 8 in FIG. 1;

FIG. 9 is an enlarged view of the selected portion 9 in FIG. 1; and,

FIG. 10 is an enlarged view of the selected portion 10 in FIG. 5.

The portions of the tube light for photography and video shown with broken lines form no part of the claimed design. The broken lines encircling portions of FIGS. 1 and 5 and encircling FIGS. 8-10, labeled 8-10 are included for annotative purposes only to show the portions of the design that are enlarged in FIGS. 8-10, and form no part of the claimed design.

1 Claim, 9 Drawing Sheets
